UNITED STATES PATENT OFFICE

2,585,324

METALLIC EAVE STRIP

Clarence L. Hutchisson, Jr., and Elwin H. Cropp,
Mobile, Ala.; said Cropp assignor to said
Hutchisson, Jr.

Application August 30, 1948, Serial No. 46,816

8 Claims. (Cl. 108—26)

1

Our invention relates generally to improvements in roof structures for buildings, and more specifically to a metallic eave strip preferably of sheet metal, which while adapted for various purposes and uses, is especially designed for use in providing a finished cornice structure on a building, which joins or unites the roofing material of the building, to insure a durable, water tight and weather tight, and leak-proof union of neat and workmanlike appearance.

The novel eave strip of our invention is adapted for use with various types of roofs built up of flexible layers or plies of roll or sheet roofing material, and the roofs may be finished with smooth surfaces as well as with gravel surfaces; with the result that the metallic eave strip is permanently incorporated or embodied as a component part of the finished roof structure.

The eave structure includes a minimum number of parts that may with facility be manufactured at low cost of production, and the parts may be assembled and installed for use with a minimum expenditure of time and labor.

The invention consists in certain novel features of construction and combinations and arrangement of parts as will hereinafter be described and more particularly set forth in the appended claims.

In the accompanying drawings we have illustrated two complete examples of physical embodiments of our invention wherein the parts are combined and arranged in accord with the principles of our invention. It will however, be understood that various changes and alterations are contemplated and may be made in these exemplifying drawings, within the scope of our claims, without departing from the principles of the invention.

Figure 1 is a vertical sectional view showing the eave strip of our invention embodied in a typical smooth surface roof. Figure 2 is a fragmentary perspective view in section showing the eave strip structure; and Figure 3 is an end view of the eave strip per se.

Figure 4 is a view similar to Fig. 1 showing the invention embodied in a roof with a gravel surface. Figure 5 is a detail fragmentary perspective in section illustrating the eave strip before installation; and Figure 6 is an end view of this eave strip. Figs. 7 and 8 are detail perspective views.

In order that the general relation and utility of parts may readily be understood we have shown in Figs. 1 and 4 a portion of a conventional roof sheathing S, the end of a rafter R, and the face

2

strip or facia F usually employed at the eaves or cornice of a building structure.

In the preferred form of the invention shown in Figs. 1, 2 and 3, we employ a sheet metal cornice structure, eave strip, or edging fashioned in suitable manner by power operated dies or rollers or a sheet-metal break with an upper horizontal roof flange 1, and a vertical front wall plate 2. In the process or operation of shaping the angular sheet or strip a return bend 3 is fashioned into a double-thick flange 4 that is outwardly spaced to provide an exterior inverted groove, channel or trough 5.

For attaching the sheet metal strip to the wood face strip F, the front wall plate 2 may be punched with a series of nail holes as 6, or the holes may be punched by hand with a suitable tool, and after the angular strip is fitted over the cornice structure, the wall plate 2 is fastened to the face board as by nails N. These nails may also be utilized, as indicated in Fig. 1, for attaching a conventional gutter G to the front of the cornice structure, or frame board F.

Before fitting and fixing the eave strip in place, the strip is equipped with one, or more, folded flexible fastening or anchoring strips or sheets, that are clamped and anchored within the inverted trough, as disclosed in Fig. 2. These strips may be fashioned of felt, water-proof fabric, or other suitable material, and they are folded over an anchoring wire or rod 7, which clamps the bend of the strip at 8 within the upper end of the inverted trough, leaving the edge flaps 9 and 10 hanging loosely from the anchoring rod and trough.

The anchoring rod or wire spline 7 may be set within the eave strip in any suitable manner to support the folded sheet or strip prior to the merging of the flaps 9 and 10 with the roof structure; and the vertical abutting edges of the eave strips may be united by a joint plate 11 shown in Fig. 7.

By means of headed rivets, as 12, passed transversely through the inverted trough, the anchoring strips are rigidly clamped between flange 4 and the front wall plate 2 with the flange 4 pressed and held in desired position against the front wall plate, and leaving the flaps 9 and 10 in position to be upturned over the top surface of the cornice structure.

The roof flange 1 is fastened down on top of the sheathing S, as by nails N driven through holes 13, and, together with the nails of the front wall plate, the angular metal strip is rigidly fastened with the closed upper wall of the trough.

approximately in the plane of the top of the sheathing S.

The flap 9 of the folded sheet or strip is passed upwardly and around the trough, extended over and beyond the roof flange 1, and laid in or built into the roofing structure, which is here shown as including three plies or layers 14, 15, and 16. The anchoring or joint flap 10 is also folded upwardly over the trough and laid between the second and third plies or layers of the sheet roofing material, and thus jointed to and embedded in the roofing structure as a component part thereof.

The anchoring flaps and the plies or layers are cemented down and fixed in place by a coating of asphalt 17, or other similar coatings, in the usual manner for fixing or laying the sheets or rolls of roofing material, to form the roof structure, and the joint or eave-edge of the roof structure is thus protected and anchored to insure a strong and durable weather-tight and water-tight or water-proof roofing.

The end of one of the lengths of edge strip may be slightly splayed to receive the ends of the plies of fabric and telescoped into the plies of fabric of the adjoining length of edging, and at this point there would be four plies of fabric at the lap above the joint plate 11.

The number of anchoring strips 9, 10, of the water-proof fabric may be changed and determined by the number of plies or layers of the roof structure, and the number of plies of sheet roofing material is determined by the desired life or durability and type of the roof structure. As thus anchored, should the roof buckle, the eave-edge of the roof remains fixed and is proof against leaks; and the roof is tied down so that the wind cannot get under the eave-portion to lift the roof.

In Figs. 5 and 6 where a front wall or guard is provided for a gravel surface roof made up of layers or plies of sheets or rolls, the roof flange 1 and the front wall plate 2 are fashioned with an inner double-thick flange 18 that forms an inverted trough 19 above the roof flange. The anchoring wire or spline 7, within the trough clamps the water-proof fabric or anchoring strip so that its flap 10 is laid and cemented down over the roof flange 1, and extends between the edges of the plies 14 and 15, while the flap 9 is fixed between the roofing layers or plies 15 and 16. The joint plate 11 in this form of the invention is provided with a hooked end or upper rounded flange 11a that fits over the inverted trough, and the plate is fastened by nails with the front wall plate to the front face board F.

By means of the anchoring flaps, the plies or layers of the roof are rigidly anchored and cemented together with asphalt, as 17, or by the use of other suitable compositions or materials; and the gravel surface 20, embedded in tar, asphalt, or other cementing composition, provides a cover for the roof that is guarded by the use of the inverted trough. The water proof and weather proof guard or cornice rail thus affords a leak proof finish of workmanlike and artistic appearance for the eaves portion of a roof, and the roofing material is confined and retained at all sides of edges, by the guards against displacement.

Having thus fully described our invention, what we claim as new and desire to secure by Letters Patent is:

1. An integral eave-strip comprising an upright attaching plate for a front wall and an

angular flange for attachment to a roof top forming an angular corner, and an anchoring flange forming an inverted open-bottom U-shaped trough extending in a plane parallel with the attaching plate along the angular corner.

5. An integral eave-strip comprising an upright attaching plate for a front wall and an angular flange for attachment to a roof top forming an angular corner, and a depending anchoring flange forming an open bottom inverted U-shaped trough extending in a plane parallel with the attaching plate along the angular corner.

15. An integral eave-strip comprising an upright attaching plate for a front wall and an angular flange for attachment to a roof top forming an angular corner, and an upper anchoring flange forming an inverted U-shaped trough having an inner free edge terminating above the 20 angular flange and extending in a plane parallel with the attaching plate along the angular corner.

25. An integral eave-strip including an upright plate for attachment to a front wall and an angular flange for attachment to a roof top forming an angular corner, an inverted U-shaped anchoring flange forming an open-bottom trough extending along the angular corner in a plane parallel with the plate, and longitudinally spaced 30 transversely extending tieing elements uniting the anchoring flange and the plate.

35. In anchoring means for a building roof, the combination with a roof structure, an eave-strip including a front upright wall plate and an angular roof flange terminating in a horizontal anchoring flange depending from the roof flange and spaced from and in parallelism with the wall plate, of a flexible anchoring sheet embedded in the roof structure, and means retaining an edge 40 portion of the anchoring sheet between the upright plate and the anchoring flange.

45. In anchoring means for a building roof, the combination with layers of roof-sheets, an eave-strip having an upright wall plate and an angular roof flange terminating in a horizontal anchoring flange depending from the roof flange in spaced parallelism with the wall plate, of a flexible anchoring sheet embedded in the roof-sheets and having an edge portion between the wall 50 plate and the anchoring flange, and an anchoring wire coacting with the edge portion for retaining said portion within the anchoring flange.

55. In anchoring means for a building roof, the combination with layers of roof-sheets, a metallic eave-strip and means for fastening it to a building, and an anchoring flange integral with the eave-strip, said flange extending laterally in a vertical plane to form an inverted U-shaped trough, of a flexible anchoring sheet embedded in the roof-sheets with its outer edge confined within the trough, a retaining wire for said edge enclosed by the trough, and transversely arranged rivets uniting the anchoring flange and eave-strip located below the wire.

60. 8. In anchoring means for a building roof, the combination with a roof-structure, a metallic eave-strip and means for fastening it to a building, and an anchoring flange integral with the eave-strip, said anchoring flange extending laterally in a vertical plane and forming an inverted U-shaped trough above the eave-strip, of a flexible anchoring sheet embedded in the roof-structure with its outer edge confined within the trough, a retaining wire for said edge and en-

closed within the trough, and transversely arranged rivets uniting the anchoring flange and the eave-strip located below the wire.
